[57] CLAIM

The ornamental design for a combined bottle cap and dust cover, as shown.

DESCRIPTION

FIG. 1 is a top plan view of a combined bottle cap and dust cover showing our new design;

FIG. 2 is a front elevation view thereof;

FIG. 3 is a side elevation view thereof;

FIG. 4 is a bottom plan view thereof; and,

FIG. 5 is an enlarged cross-sectional view thereof, taken in the direction of the arrows along line 5—5 of FIG. 2.

FIG-1

FIG-2

FIG-3

FIG-4
